SURGICAL DEVICE

Ernest Radcliff, Jonesboro, Ill.

Application October 7, 1937, Serial No. 167,725

2 Claims. (Cl. 128—345)

The present invention relates generally to surgical instruments, and more specifically to an obstetrical device embodying a self-retained perineal retractor adapted to painlessly hold in a laterally spread position the female vaginal orifice and any surgical incision or spontaneous laceration of the perineum.

During childbirth the vaginal mucous membrane, the perineal body, and covering skin are often torn by the passage of the child, or are cut to allow easier and quicker passage of the child. After the child has been delivered it is necessary for the well-being of the mother that this cut or tear be sutured. Quite often the doctor in attendance, particularly in rural districts, is without assistance. In those cases where he is fortunate enough to have the services of only one competent individual, it usually transpires that this individual must direct all of his or her attention to the care of the newborn child. It is a difficult procedure, unassisted, to properly sew a cut or tear in the genital orifice or perineum, after childbirth, since the orifice must be held open for washing and sewing and obviously the doctor needs some one or something to assist him.

Heretofore, certain devices have been devised for the purpose of maintaining the vaginal orifice and torn or cut perineum laterally spread during a repair operation. However, none of these is of general practicality, either because of a construction which hinders the doctor, as by interposing some portion of the instrument between the physician and the laceration or cut to be sutured; or because of pain inflicted on the patient by the instrument; or because of some other impractical feature.

Therefore, it is an object of the present invention to provide a surgical instrument which is adapted to spread and to maintain in spread position the female genital orifice, which is particularly useful after childbirth to hold the genital orifice in spread position so that the doctor can, unassisted, sew any tear which may have been caused by the birth of the child, or any incision made to facilitate childbirth.

Another object is to provide a surgical instrument which is adapted to spread and to maintain in spread position the female genital orifice and damaged perineum, which is self-retained in its operative position.

Another object is to provide a surgical instrument which is adapted to painlessly spread and maintain in spread position the female genital orifice.

Another object is to provide a surgical instrument which is adapted to be inserted into the female vagina and which is adapted to laterally spread the vaginal walls and to maintain the

tissues retracted through self-retained contact with the descending rami of the pubic bones.

Another object is to provide a surgical instrument which is adapted to assist a doctor in repairing a tear or cut in the vaginal mucous membrane or perineal body or the covering skin.

Another object is to provide a surgical instrument adapted to assist a doctor in single-handedly repairing a tear or cut in the female genital orifice or perineal body or the skin covering it, which instrument is so constructed that the manipulative parts thereof extend upwardly from the individual being treated when in a supine position in a manner to be out of the way of the doctor so as to permit complete freedom for his work.

Another object is to provide a surgical instrument adapted to assist the doctor in repairing a tear or cut in the female genital orifice, the perineum body, or the skin covering it, is adapted to be operatively disposed for freedom of movement of the doctor whether the patient be upon a flat hard surface or a resilient interfering mattress.

Another object is to provide a surgical instrument of the pivoted twin lever type which includes a spring normally biasing the twin levers to one extreme position, said spring being located relative to the pivot so that the force required to move the levers from the biased position to the other extreme position diminishes as the levers are moved, the greatest effective force exerted upon the pivoted levers by the spring through its effective lever arm being exerted in the said biased position.

Another object is to provide a surgical instrument constructed of light strong material so that it will not injure delicate tissues against which it is adapted to be placed.

Another object is to provide a surgical instrument which is simple to use, yet which is thoroughly efficient and effective in the performance of its intended functions.

Other objects and advantages will appear from the following descriptions, taken in conjunction with the accompanying drawing, in which:

Fig. 1 is a front elevation of a preferred embodiment of the present invention, the pivoted members being shown in spread relation;

Fig. 2 is a side elevation of the device shown in Fig. 1;

Fig. 3 is a rear elevation of the device shown in Fig. 1;

Fig. 4 is a plan view of the device shown in Fig. 1;

Fig. 5 is a front elevation of the device shown in Fig. 1, the pivoted members being disclosed in closed relation;

Fig. 6 is a plan view of the device shown in Fig. 1.

Fig. 1, the pivoted members being disclosed in closed relation:

Fig. 7 is a section on the line 7—7 of Fig. 1;

Fig. 8 is a section on the line 8—8 of Fig. 3;

5 Fig. 9 is a view of a blank from which the pivoted members of the present invention are constructed; and,

10 Fig. 10 is a view of the associated bones of the pelvis of a female, portions of the internally disposed elements of a preferred form of the present invention being shown in operative engaging relation with the descending rami of the pubic bones.

15 Referring to the drawing more particularly by reference numerals, 15 indicates generally a preferred embodiment of a surgical instrument constructed in accordance with the teachings of the present invention. The instrument 15 includes two pivoted members or levers 16 and 17, which are constructed from identical blanks of a configuration shown in Fig. 9, and, therefore, only one member will be described. Each member includes a base or pivot segment 18 having an aperture 19 therethrough, a peripheral indentation 20, and a projection 21.

20 A handle segment 22 shown of circular form is connected to the pivot segment 18 by a neck portion 23, the plane of the handle segment 22 being at right angles to the plane of the pivot segment 18. Extending from another side of the pivot segment 18 is a tab 24 having an aperture 25 therein, the tab 24 being returned 90° relative to the segment 18.

25 A connecting segment 28 extends from a third side of the pivot segment 18 and is disposed at an angle thereto so that the plane thereof is at an angle of substantially 40° to the plane of the pivot segment 18. Extending from that end of the connecting segment 28 remote from the pivot segment 18 is a curved prong segment or blade 29, the mean plane of which is substantially at 90° to the plane of the connecting segment 28. The prong segment 29 terminates in a tip 30 which is curved in a manner reverse to that of 30 the prong 29.

35 The members 16 and 17, while constructed from identical blanks, are, of course, oppositely bent in construction in order to provide cooperating members. A bolt 33 extends through the aligned apertures 19 of the members 16 and 17 (Fig. 7), a washer 34 being disposed about the bolt 33 and between the members 16 and 17 to prevent undue friction. A nut 35 is disposed upon the threads of the bolt 33 and in tightened 40 relation maintains the members 16 and 17 in pivotal relation upon the bolt 33.

45 A spreading mechanism generally designated 38 (Fig. 8) is provided. Through one aperture 25 extends a brad 39, or the like, having a head 40 abutting against the tab 24 and having an aperture 41 through a shaft portion 42. Extending through the other aperture 25 is a knurled thumb screw 43 having a head 44 abutting against the tab 24. The knurled thumb screw 43 has a threaded shank 45 upon which is threadably mounted a sleeve 46 having an aperture 47 adjacent the free end thereof. A helical tension spring 48 has one hooked end 49 extending through the aperture 47 and a second hooked end 50 extending through the aperture 41. The shank 45 is of relatively considerable less diameter than the diameter of its associated aperture 25 to allow the spring 48 to maintain a substantially straight line between the apertures 25 during use of the device. Otherwise, the spring 48

would be buckled. The tension of the helical spring 48 is, of course, adjustable through manipulation of the knurled thumb screw 43. The helical spring 48 tends at all times to draw the members 16 and 17 apart, or to maintain them in the relative positions shown in Figs. 1, 3, and 4. The members 16 and 17 are limited in this open direction of pivotal movement by the neck portion 23 of the member 16 striking the projection 21 of the member 17 and the neck portion 23 of the member 17 striking the projection 21 of the member 16.

50 The spring 48 is located relative to the pivot bolt 33 so that the maximum effect of the spring 48 is obtained when the elements of the instrument 15 are in their open positions, as shown in Fig. 1. As the handle segments 22 are manually, or otherwise, moved together, the force necessary to effect the movement becomes less and is a minimum when the elements of the instrument 15 are in the closed position shown in Fig. 5. This is true because, although the actual force of the spring per se increases as the instrument 15 is closed, the lever arm of application of this force decreases in greater proportion. This what may be termed differential movement is necessary in order that the handle segments 22 can be short enough to obviate their amounting to obstructions, yet of sufficient length to actuate the device, for in substantially 35 open position there must be sufficient spring force exerted to maintain the instrument 15 in operative position.

55 An inspection of a blank 55 shown in Fig. 9 in conjunction with Figs. 1-6 will clarify the preferred specific shape of the finished members 16 and 17.

60 In forming a member 16 and 17 the handle segment 22 of the blank 55, which is stamped or otherwise cut of a configuration shown in Fig. 9 from a flat piece of stainless sheet metal, or other material, is twisted substantially about the dotted line 56 (Fig. 9) to dispose it in a plane at 90° to the plane of the pivot segment 18. The tab 24 is bent along substantially the dotted line 57 through 90°, the radius of curvature of the bend being a substantial minimum for the material used. The connecting segment 28 is bent substantially along the dotted line 58 to the side of the pivot segment 18 opposite to that toward which the tab 24 is bent until the plane of the connecting segment 28 is substantially at 40° to the plane of the pivot segment 18, the radius of the bend being, as in the case of the bend of the tab 24, a substantial minimum. The 65 prong segment 29 is moved substantially about the dotted line 59 towards the pivot segment 18 through substantially 90°, the radius of bend being large as compared to the aforementioned bends to provide smoothness. The prong segment 29 is curved throughout that portion of its length between the line 59 and a dotted line 60. The tip 30 of the prong segment 29 is arced on a curve reverse to the curve of the main body of the prong segment 29, the curves meeting on 70 substantially the line 60.

75 Each blank is constructed substantially as described so that, when two members 16 and 17 are in operative associated relation, the tips 30 substantially touch and the prong segments 29 are 75 in substantially parallel relation (Figs. 5 and 6) when the instrument 15 is in closed position. When the opposed members 16 and 17 are bent or arced along the same lines, as indicated in Fig. 9, the tip 30 of the member 16 will slightly 75

overlie the tip 30 of the member 17 an amount substantially equal to a blank thickness and the thickness of the washer 34. This, of course, may be compensated for, if desirable, through changing the position of the bend line 59 of either the member 16 or the member 17. When the instrument 15 is in this closed position the connecting segments 28 are in substantially parallel planes, these planes being separated only by the thickness of a blank and the thickness of the washer 34.

However, when the instrument 15 is in opened position (Figs. 1-4), the tips 30 will be considerably farther apart than the nearest points of the opposed prong segments 29.

When the instrument 15 is in closed position (Figs. 5 and 6) the ends of the tips 30 substantially touch and the segments 29 are in adjacent relation with the bottom edges thereof closer than the top edges. However, when in open position (Figs. 1 and 3) the tips 30 are farther apart than the segments 29, and the bottom edges of the latter are farther apart than the top edges. The tips 30 become farther apart than the segments 29, for in the pivotal movement of the members 16 and 17 about the bolt 33 as a pivot the tips 30 move through a greater arc than the segments 29 since they have a greater mean radius. This movement effects an apparent twisting of the segments 29. The segments 29 accomplish the lateral dilatation of the external genitalia at the same time that tips 30 are hooking in behind the descending rami of the pubic bones. Without this motion it would be physically impossible to shape the segments 29 and the tips 30 to perform the two functions above described and to cause them to come together when the instrument 15 is closed. Did the tips 30 not come together in the closed position, it would make their introduction into the vagina very difficult and painful.

Segments 29, in the open position of the instrument 15, are set at an angle approximately the same as the angle of the two descending rami of the pubic bones; hence the segments 29 fit flatly against the broad inner surfaces of the rami and no discomfort results. As the curve of the segments 29 also causes their tips 30 to pass in behind the rami where they rest flatly against the bones, there is a painless, hooking effect that produces a firm and painless self-retention. The reverse curve of the tip 30 makes the rounded surface which rests gently upon the soft muscular structures which cover the obturator foramen, and further aids in a firm but painless self-retention.

It is apparent that there has been provided a surgical instrument which is adapted to fulfill all of the objects and advantages sought therefor.

60 Operation

With the aid of the present invention a doctor can repair a tear or cut in the female genital orifice occasioned by childbirth, or otherwise, without the help of assistants. The instrument 15 is grasped by the handle segments 22 and closed to the position shown in Fig. 5. Holding the handle segments 22 above the supine patient, the tips 30 and the prong segments 29 are inserted into the vagina. After the prongs 29 are embedded therein the pressure on the handle segments 22 is gradually released, whereupon the helical spring 48 exerts its tension force to spread

the prong segments 29 apart about the pivot bolt 33 producing rotation of segments 29 at the same time due to the relation of the segments 28 to the segments 18, until the prong segments 29 engage the descending rami of the pubic bones. This spreading action of the instrument, of course, spreads laterally the genital orifice and any tears or cuts in the perineal body or vaginal mucous membrane or skin. The shape of the prong segments 29 and their angles of disposition hold the instrument 15 in open position in the genital orifice so that the doctor can proceed single-handedly with the mending of the tear or cut. The handle segments 22 and the pivot segments 18 are disposed above the genital orifice of a supine patient so that unobstructed access may be had to the vagina. When the tear or cut has been mended the instrument 15 is removed by a procedure reverse to the procedure of insertion. The use of the instrument 15 is painless, inasmuch as there are no sharp points or angles which contact the flesh; the tips 30 and prong segments 29 are close together during insertion into the vagina; and the subsequent retaining pressure is applied by the flat side of the segments 29 against the flat inner surface of the descending rami of the pubic bones.

The structure, operation and use of the present invention is apparent from the foregoing description thereof, taken in conjunction with the drawing. It is to be understood that the foregoing description and accompanying drawing have been given by way of illustration and example and not by way of limitation, the invention being limited only by the appended claims.

What is claimed is:

1. A surgical instrument comprising a pair of members of opposed similar construction, means pivotally connecting said members, each member including a pivot segment, a connecting segment connected to the pivot segment at an angle thereto, a prong segment connected to the connecting segment at an angle thereto and extending towards and through the plane of the pivot segment, said prong being of arcuate configuration and including an arcuate tip formed on a reverse curve to the main body of the prong, the tips of the members being in substantially contiguous relation in one extreme relationship thereof, a handle segment connected to the pivot segment, and means biasing said members towards another extreme relationship.

2. A surgical instrument comprising a pair of sheet metal members of opposed similar construction, means pivotally connecting said members, each member including a pivot segment, a connecting segment connected to the pivot segment at an angle thereto, a prong segment connected to the connecting segment at an angle thereto and extending towards and through the plane of the pivot segment, said prong being of arcuate configuration and including an arcuate tip formed on a reverse curve to the main body of the prong, the tips of the members being in substantially contiguous relation in one extreme relationship thereof, a handle segment connected to the pivot segment, and means biasing said members towards another extreme relationship including a spring connected to said pivot segments between the pivotal connecting means and the handle segments.

ERNEST RADCLIFF.
